UNITED STATES PATENT OFFICE.

EDMUND LUNKENHEIMER, OF CINCINNATI, OHIO, ASSIGNOR TO THE LUNKENHEIMER BRASS MANUFACTURING COMPANY, OF SAME PLACE.

STRAIGHT-WAY VALVE.

SPECIFICATION forming part of Letters Patent No. 450,588, dated April 14, 1891.

Application filed November 13, 1890. Serial No. 371,305. (No model.)

To all whom it may concern:

Be it known that I, EDMUND LUNKENHEIMER, a citizen of the United States, residing at Cincinnati, in the county of Hamilton and State of Ohio, have invented certain new and useful Improvements in Straight-Way Valves, of which the following is a description, reference being had to the accompanying drawings, forming part of this specification.

10 My invention relates to what may be called "oscillating valves," for the reason that the passage between the pipe-connections, arranged in line with each other, is closed and opened by a pair of valve-disks operated by 15 an oscillating or rocking spindle or valve-stem which swings them into and out of line with the pipe-connections. The rocking spindle is journaled in bearings parallel with the line of the pipe-connections, and the 20 valve-disks move at right angles to such line. When swung into line with the connections to close the valve, they fit snugly against seats at the inner sides of said connections, all as shown and described in a number of 25 patents heretofore granted to me, the last of which is No. 426,539, of April 29, 1890.

My present invention consists in certain improvements in the frictional bearing for the spindle, and in a novel method of supporting one of the valve-disks, all as will be 30 herein set forth, and specifically pointed out in the claims.

In the accompanying drawings, Figure 1 is a plan view of the valve. Fig. 2 is a top view 35 of the valve-shell shown in Fig. 1 with the cap removed. Fig. 3 is a vertical section on the dotted line 3-3 in Fig. 1, looking in the direction of the arrow at right angles to said line. Fig. 4 is a vertical section on the line 40 4-4 in Fig. 1, looking in the direction of the arrow at right angles to said line. Fig. 5 is a perspective view of the two valve-disks. Fig. 6 represents details of the spindle-opening in the valve-shell and the friction-ring 45 adapted to fit therein. Fig. 7 is a perspective view of the spindle.

The same letters of reference are used to indicate identical parts in all the figures.

The valve-shell, with the exception of the 50 cap, is cast in one piece, and consists of the

chamber A, pipe-connections B B, and tubular portion C. The pipe-connections are in line with each other, as is usual in this style of valves, and are interiorly threaded to receive the pipes. The open ends of the valve- 55 shell body, through which the disks are inserted, is closed by a cap D, bolted to the body of the shell.

The valve-disks E E' are two in number, and adapted to fit and be forced against inclined seats F F' in the body of the shell. The lower disk E' has at one side an integral carrier E², by which it is supported upon the rocking spindle G, the lower rectangular end of the latter passing through a similar-shaped 60 opening in the disk-carrier, so that the rocking or oscillating movements of the spindle will be communicated to the valve-disk to swing it into and out of line with the pipe-connections to close and open the valve. The 65 lower end of the spindle rests upon the shell at the bottom of the tubular portion C, and is provided with a pin fitting a seat in the shell to hold the spindle true in its bearings.

The upper disk E is not supported by the 70 spindle as is the lower one, but is supported entirely by the lower disk itself. There is a bearing H between the two disks at their centers, and on its side next the spindle the upper disk is provided with a pendent pin I, 75 concentric to said disk and extending loosely through a hole in the carrier E² of the lower disk. The central bearing H and loose eccentric connection by the pin I allow the disks sufficient play relatively to each other to permit them to properly adjust themselves to the inclined seats F F' when the valve is closed. At a point opposite or nearly opposite the pin I the upper disk is provided on its under side 80 with a lug J, which fits loosely between two lugs K K on the upper side of the lower disk. The purpose of this connection of the two disks by the lugs J K is to prevent the upper disk becoming displaced from its proper position on the lower disk when the valve is 85 opened or closed.

The valve-spindle G is provided with an integral friction-collar L, having a beveled upper side. Fitting snugly around the cylindrical portion of the spindle above the fric- 90 95 100

tion-collar is a screw-plug M, screwed into the spindle-opening in the shell and affording the upper bearing for the spindle. Surrounding the spindle immediately above the collar L, 5 the two bearing-surfaces being preferably ground, is a ring N, Fig. 6. This ring has ears upon its opposite sides, which fit within grooves in the sides of the opening Fig. 6, and prevent the ring turning. Between the 10 ring and the lower side of the screw-plug M is interposed suitable packing O.

By tightening up the screw-plug M the friction-ring N may be made to bear against the collar L and likewise the bottom of the spindle against the shell with any desired degree of pressure, so that greater or less resistance may be offered to the turning of the spindle. When the spindle is turned by the handle P applied to its upper end to open 15 the valve to any degree desired, the disks will remain at that point when the handle is released and will be held there against ordinary shocks or jars.

The non-revolv^ole ring N prevents the 20 movements of the collar L and spindle from being communicated to and loosening the plug M. It will of course be understood that said ring may be held from turning by other means than by the ears on it and the grooves 25 in the spindle-opening.

As before stated, the connection of the disks E E' by the lugs J K K is only for the purpose of preventing displacement of the upper disk and may be dispensed with where other 30 means are employed for the purpose. Thus in another application filed simultaneously with this and bearing serial number 371,306, I have shown a rectangular lug and hole substituted for the round pin I and the round 35 hole in the carrier E², which renders the connection above referred to unnecessary.

My present invention has certain advantages over the constructions shown by the 40 patents heretofore issued to me. In my patent No. 354,019 only one valve-seat and one valve are shown and the valve-seat is not an inclined one. The connection of the valve with its carrier by means of the flanges outside of the valve did not hold the latter 45 positively in place so that it was non-revolv^ole, as is the disk E of this case, and which by its positive eccentric connection with the disk E' is constantly held in one position relative thereto; but the greatest advantage resulting 50 from the present construction over that shown by the said patent is in the greater symmetry, cheapness, and compactness, as the

flanges outside of the valve-disk of the said patent, and by which said valve-disk is held in place on its carrier, require a valve-shell 60 of a diameter materially greater than is required for my improved valve. In the valve shown by my patent No. 426,539 the valve-disks both have connections with their oscillating spindle and one is not supported by 65 the other, as in the present case, this new construction being cheaper than that shown by said patent, as well as more desirable in that it affords more freedom of movement of one disk relative to the other. 70

Having thus fully described my invention, I claim—

1. In a valve such as described, the combination of the shell having the two inclined seats F F', the rocking spindle G, parallel with the line of the pipe-connections, the valve-disk E', supported on said spindle by its integral carrier E² and co-operating with the inclined seat F', the non-revolv^ole disk E, supported by the disk E' and co-operating 80 with the inclined seat F, a central bearing H between the two disks, and an eccentric connection between said disks by the pin I on one and a corresponding hole in the other for positively preventing displacement of the 85 disk E, substantially as described.

2. In a valve such as described, the combination of the shell having the two inclined seats F F', the rocking spindle G, parallel with the line of the pipe-connections, the valve-disk E', supported on said spindle by its integral carrier E² and co-operating with the inclined seat F', the non-revolv^ole disk E, supported by the disk E' and co-operating 90 with the inclined seat F, a central bearing H between the two disks, an eccentric connection between the disks by the pin I on one and corresponding hole in the other, and a second eccentric connection between them, as by the lugs J K K, substantially as described. 95

3. In a valve such as described, the combination of the shell, the rocking spindle G, provided with the friction-collar L, the non-revolv^ole friction-ring N, bearing upon said 105 collar, the screw-plug M, and the packing O, interposed between the plug M and the ring N, substantially as and for the purpose described.

EDMUND LUNKENHEIMER.
